UNITED STATES PATENT OFFICE.

WALTER T. GODDARD, OF HAMILTON, ONTARIO, CANADA, ASSIGNOR, BY MESNE ASSIGNMENTS, TO LOCKE INSULATOR CORPORATION, OF BALTIMORE, MARYLAND, A CORPORATION OF MARYLAND.

STRAIN INSULATOR.

Application filed October 25, 1919. Serial No. 333,157.

To all whom it may concern:

Be it known that I, WALTER T. GODDARD, of Hamilton, in the Province of Ontario and Dominion of Canada, have invented certain new and useful Improvements in Strain Insulators; and I do hereby declare the following to be a full, clear, and exact description of the same, reference being had to the accompanying drawings, forming a part of this specification, and to the reference numerals marked thereon.

My present invention relates to electrical appliances and more particularly to insulators of the kind usually employed to support heavy loads on high tension lines and it has for its object to provide an improved construction in which the attached parts of the insulator, usually comprising a silicious frangible element and a metallic attaching element, are held together in a way that distributes the strain through the mass of the frangible element. To these and other ends the invention resides in certain improvements and combinations of parts all as will be hereinafter more fully described, the novel features being pointed out in the claims at the end of the specification.

In the drawings:

Figure 1 is a side view of a strain insulator unit partially broken away, constructed in accordance with and illustrating one embodiment of my invention;

Figure 2 is an enlarged fragmentary view of a head of the insulator with the cap removed, together with one half of the arcing ring;

Figure 3 is an enlarged top view of the insulator with the cap removed;

Figure 4 is a fragmentary section on the line 4—4 of Figure 3;

Figure 5 is an enlarged top view of the insulator partly broken away;

Figure 6 is a horizontal section on the line 6—6 of Figure 4, and

Figure 7 is an enlarged fragmentary view showing a detail of the cap.

Similar reference numerals throughout the several views indicate the same parts.

This invention is an improvement on that described and claimed in my prior and pending application, Serial No. 273,145 filed January 25, 1919, which discloses the functions and advantages of a certain method of lacing the frangible silicious element of a

strain insulator to its connected part so that the strains will be distributed uniformly through the frangible mass to enable it to withstand heavier loads. I will therefore not go into detail in describing this part of the present disclosure.

The insulator I have illustrated in the present instance embodies a ribbed or flanged cylindrical column 1 of frangible silicious material such as the ordinary porcelain used in such instances with attaching a ring 2 at each end for connection with a support or with the body to be supported or with another unit of the same nature, as the case may be, these units being often used in multiples and connected together. As both ends or heads embodying the rings 2 are alike, a description of one will suffice for both.

Referring more particularly to Figures 2, 3 and 4, the solid porcelain enlargement 3 at the head of the column 1 is pierced by a number of annularly disposed staggered apertures 4 and on top of the head is placed a concentric disc 5 having an embossed perforated center 6, to receive the ring bolt 7 having the head 8 engaging beneath the embossed portion. At the margin of the disc 5 is an annular rib 8^a on the inner circumference of which the disc is pierced by a ring of apertures 9. A flexible continuous cable 10 having its ends suitably fastened together as indicated at 11 in Figure 3, is laced through the openings 4 and 9 of the porcelain and the attaching disc so that its loops embrace the portions 11^a of the former and extend around the annular rib 8^a of the latter. The said flexible member can thus slide around and adapt itself so that it bears with an equal pressure at all points and the strain is distributed through the mass of the porcelain.

It is desirable, in order to effect a true self-adjustment of the flexible member, that it be subjected to a preliminary strain prior to the imposition of the strains created by actual use of the insulator in its intended capacity and in the practice of my present invention, I provide devices for doing this which devices are further capable of imposing a greater separating strain between the porcelain and its attaching member without imposing upon the former any tensile strain whatever. To these ends, I thread

into the rib portion 8^a of the disc 5 at equidistant circumferential intervals a plurality of jack screws 12 so that their points bear against the porcelain in the region of the 5 portions 11^a thereof that are embraced by the lacing 10 and upon which the pull of the latter is exerted at a lower point. These screws are manually tightened to the desired point and secured by lock nuts 13. They 10 operate not only to adjust the lacing in the manner pointed out, but they also hold it so taut that the two elements 1 and 5 are practically rigidly connected as no relative movement is permitted between them. In tightening the screws, it will be noted that their 15 pressure is exerted against the portions 11^a and in opposition to the contact of the lacing therewith which acts against the screw on the opposite side. The actual strain on the 20 porcelain is therefore one of compression which this substance is able to withstand to a high degree and is not in the nature of a tensile strain such as would be exerted on the portions 11^a if the lacing was used 25 without the compression member to resist the pull imposed by the use of the insulator as a suspension support. Therefore, the screws, to whatever degree they may be tightened do not impose upon the porcelain 30 any strains detracting from its capability of withstanding the strains of actual use.

The flexible member or lacing 10 would ordinarily be composed of metal and as such, would probably constitute the arcing point 35 of the insulator, thereby impairing its strength. I therefore provide the metallic arcing ring 14 on the lower portion of the insulator head 3 which ring I make of two semi-circular sections as shown in Figure 6, 40 bolted together at 15 by webs 16 connecting them to semi-circular inner members 17 jointly forming a band that encircles and secures the ring to the head. I then fit over the head an annular cap 18 that extends 45 from the central portion of the disc 5 over the lacing 10 completely housing it and downwardly into electrical contact with the structure of the arcing ring 14 for which purpose it is slotted at 19 as shown in Figure 7 to fit over the webs 16. It will be seen 50 that this cap and the ring fully protect the lacing 10 and prevent a possible arc from reaching it.

While I have illustrated my invention in 55 connection with an insulator of the suspension type, those skilled in the art will recognize that its application is possible to supporting or pin type insulators.

I claim as my invention:

60 1. In a strain insulator, the combination with a frangible element of insulating ma-

terial having apertures therein and a connected element, one of which is supported by the other through the medium of a continuous flexible member laced through the 65 apertures in the frangible element, of means operatively imposed between the elements 70 for exerting a separating strain thereon to stretch the flexible member and distribute the strain among the points of bearing of said 75 flexible member on said frangible element.

2. In a strain insulator, the combination with a frangible element of insulating material having apertures therein and a connected element, one of which is supported 80 by the other through the medium of a continuous flexible member laced through the apertures in the frangible element, of a device for stretching said flexible member, said device being arranged to act against one element and react against the other to exert a separating strain thereon, and being adapted to apply to the frangible element a compressive force in opposition to the force exerted by the lacing. 85

3. In a strain insulator, the combination with a frangible element of insulating material having apertures therein and a connected element, one of which is supported by the other through the medium of a continuous flexible member laced through the 90 apertures in the frangible element, of a manually operable stretching device acting against one element and reacting against the other to exert a separating strain thereon 95 causing the flexible member to be stretched so that its application of force to the frangible element is distributed.

4. In a strain insulator, the combination with a frangible element of insulating material having apertures therein and a connected element, one of which is supported by the other through the medium of a continuous flexible member laced through the 100 apertures in the frangible element, of a jack screw threaded into the connected element and bearing against the frangible element to exert a separating strain operating to stretch the flexible member and distribute its application of force among its bearing points. 105

5. In a strain insulator, the combination with a frangible element of insulating material having apertures therein and a connected element, one of which is supported by 110 the other through the medium of a continuous flexible member laced through the apertures in the frangible element, of an arcing ring secured to the frangible element adjacent to the lacing and a cap for the connected element housing the lacing and electrically 115 joined to the arcing ring.

WALTER T. GODDARD.
